United States Patent

Des. 235,744
Patented July 8, 1975

235,744

TRAFFIC HAZARD MARKER

Will Clarke England, 7310 Easterrest,
Austin, Tex. 78752

Filed Jan. 11, 1974, Ser. No. 432,471

Term of patent 14 years

Int. Cl. D10—06

U.S. CL. D10—109

FIG. 2

FIG. 1

FIG. 3

FIG. 4

FIG. 5

FIG. 1 is a perspective view of a traffic hazard marker showing my new design;

FIG. 2 is a bottom plan view thereof;

FIG. 3 is a top plan view thereof;

FIG. 4 is a vertical cross-section taken on line 4-4 of FIG. 3;

FIG. 5 is a fragmentary cross-section taken on line 5-5 of FIG. 4.

I claim:

The ornamental design for a traffic hazard marker, substantially as shown.
